UNITED STATES PATENT OFFICE.

HIRAM E. BUTLER, OF JAMESTOWN, NEW YORK.

DESIGN FOR A SAD-IRON HOLDER.

SPECIFICATION forming part of Design No. 25,581, dated June 2, 1896.

Application filed October 3, 1895. Serial No. 564,578. Term of patent 7 years.

To all whom it may concern:

Be it known that I, HIRAM E. BUTLER, a citizen of the United States, residing in the city of Jamestown, in the county of Chautauqua and State of New York, have invented and produced a new and original Design for Sad-Iron Holders, of which the following is a specification, reference being had to the accompanying drawings, showing a part thereof.

Figure 1 is a side elevation of the design. Fig. 2 is a sectional plan view.

The leading feature of my design is its general contour, being open at the bottom in the form of jaws, as shown in Fig. 1, then

extending up in a long curve, which curve is much straighter near the bottom than toward the top. It is flattened out near the top and has oval projections D D on the sides and upright projections A on the top, as shown in Figs. 1 and 2.

What I claim is—

The design for sad-iron holders, substantially as shown and described.

HIRAM E. BUTLER.
